United States Patent Office.

THOMAS LYONS, OF BROOKLYN, NEW YORK, ASSIGNOR TO HIMSELF AND JOSEPH B. KING, OF THE SAME PLACE.

Letters Patent No. 70,099, dated October 22, 1867.

IMPROVED CURTAIN-FIXTURE.

The Schedule referred to in these Letters Patent and making part of the same.

TO ALL WHOM IT MAY CONCERN:

Be it known that I, THOMAS LYONS, of Brooklyn, in the county of Kings, and State of New York, have invented certain new and useful Improvements in Window-Shade Fixtures; and I do hereby declare that the following is a full, clear, and exact description of the same, reference being had to the accompanying drawings, making a portion of this specification, in which—

Figure 1 is a longitudinal transverse section of a shade-fixture made according to my invention.

Figure 2 is a longitudinal section of the same taken at right angles to fig. 1.

Figure 3 is a face or front view showing a modification of the same.

Similar letters of reference indicate corresponding parts in all the figures.

This invention belongs to that class of devices designed to hold in position the cords of window-shades, and its object is to enable the same or nearly the same tension to be exerted on the cord, whether the slide of the device be placed higher or lower with reference to the frame thereof, to suit the length of the cord, instead of increasing the tension in proportion to the upward movement of the slide, as in those cases where a spiral spring is used.

The invention consists in a novel construction and arrangement of a spring with reference to a stud on the aforesaid slide and the frame of the device, whereby the desired object is secured.

To enable others to understand the nature and construction of my invention, I will proceed to describe it with reference to the drawings.

The frame of the fixture is shown at A, and may be attached in a vertical position to the side of the window-frame, by screws passing through suitable holes, a, at each end thereof. Formed centrally in this frame is a longitudinal slot, b, which is widest at its rearmost side, or, in other words, of a dove-tail form in its cross-section. C represents a flat slide, which is situated upon the frame A, longitudinal therewith, and furnished at its rearmost side with a spur, c, of a dove-tail form, and fitted into the slot b in such manner that the said slot is caused to act as a guide for the slide C in the longitudinal movements thereof, and also to hold the same in proper contact with the frame A, the said slide being furthermore steadied at its lower end by two projections, d, formed upon the frame A, and situated one upon each side of the slide. Provided upon the forward side of the slide, near the upper end thereof, is a friction-roller, e, over which the lower end of the cord which operates to raise or lower the shade is passed when the device is in use, and which is kept in place upon its pivot by a broad head, a, secured upon the end of the latter. The tension-spring is marked D in the drawings, and has its outer end portion coiled around a pin, m, fixed near one edge of the frame A, while its main length may be made slightly curved, as shown more plainly in fig. 2, the free extremity of the said spring resting upon a stud, g, projecting forward from the lower end of the slide. This spring, with the adjacent portion of the slide, may be covered by a front plate, n, attached to the frame A in front of the said parts, by the bent or angular ends of the said plate.

When the fixture is in use, the spring D, by pressing downward the slide C, exerts the requisite pressure upon the cord by which the shade is raised or lowered; and, inasmuch as the change in the position of the spring, caused by the longitudinal movement of the slide, necessitates but a slightly increased coiling of the coiled portion of the said spring, it follows that the pressure of the spring, and consequently the tension exerted by the slide upon the cord, will vary but very little, whether the slide be situated higher or lower, to suit the length of the aforesaid cord, the practical operation of the device being thus rendered much superior to those in which a spiral spring is employed to operate the slide, and in which the compression of the spring produces an increased tension upon the cord.

If desired, instead of with a single spring, as shown in figs. 1 and 2, and hereinbefore described, the fixture may be furnished with two such springs, situated at opposite sides of the slide, but with their free extremities resting upon the same stud g, all as indicated in dotted outline in fig. 3, the operation of each spring being the same in this case as in that where a single spring is used as set forth.

What I claim as my invention, and desire to secure by Letters Patent, is—

The tension-spring, constructed as described, and arranged in relation with the stud m, the slide C, and the frame A, substantially as and for the purpose specified.

THOMAS LYONS.
